(57) **CLAIM**

The ornamental design for energy meter as shown and described.

DESCRIPTION

Fig. 1 is a perspective view of the front, top, and right side of an energy meter;

Fig. 2 is a front view of the energy meter;

Fig. 3 is a left side view of the energy meter;

Fig. 4 is a rear view of the energy meter;

Fig. 5 is a top view of the energy meter; and

Fig. 6 is a bottom view of the energy meter.

The portions of the energy meter shown in broken lines form no part of the claimed design.
